(57) **CLAIM**

The ornamental design for a synthesizer, as shown and described.

DESCRIPTION

FIG. 1 is a top perspective view of a synthesizer showing my new design.

FIG. 2 is a front view thereof.

FIG. 3 is a back view thereof.

FIG. 4 is a left side view thereof.

FIG. 5 is a right side view thereof.

FIG. 6 is a top view thereof; and,

FIG. 7 is a bottom perspective view thereof.

The broken lines in FIGS. 1-7 represent the portions of the design that form no part of the claim.

1 Claim, 5 Drawing Sheets
